UNITED STATES PATENT OFFICE.

PETER M. MELICK, OF NEWARK, NEW JERSEY.

DESIGN FOR A NECKTIE-FASTENER.

SPECIFICATION forming part of Design No. 13,886, dated May 1, 1883.

Application filed February 17, 1883. Term of patent 7 years.

To all whom it may concern:

Be it known that I, PETER M. MELICK, a citizen of the United States, residing in the city of Newark, county of Essex, and State of New Jersey, have invented certain new and useful Improvements in Designs for Necktie-Fasteners, fully described and represented in the following specification and the accompanying drawings, forming a part of the same.

10 The form I have designed for a necktie-fastener is that of a three-cornered piece having its larger side curved or curled to one side at the middle, and the opposite point slotted.

In the drawings, Figure 1 is an outside view 15 of the fastener; and Fig. 2, an end view, the necktie-bow being indicated in each figure by dotted lines.

A A are the two ends or side tongues, curved upward as they extend outward.

B is the central part of the upper edge, 20 curved forward, as shown in Fig. 2, over the silk bow F.

C C are two tongues at the bottom, one at each side of a narrow slot, D.

I am aware that fasteners of form somewhat 25 similar to mine have already been made; but as my design consists partly in the forward curl given to the upper edge at B,

I claim the same as follows:

The design for a necktie-fastener, as herein 30 shown and described.

In testimony whereof I have hereunto set my hand in the presence of two subscribing witnesses.

PETER M. MELICK.

Witnesses:

THOS. S. CRANE,
HENRY F. GÖKEN.
